UNITED STATES PATENT OFFICE.

ULRICH EBERHARDT, OF NEWARK, NEW JERSEY.

DESIGN FOR A RAM FOR PLANING-MACHINES.

SPECIFICATION forming part of Design No. 25,804, dated July 21, 1896.

Application filed March 10, 1896. Serial No. 582,658. Term of patent 14 years.

To all whom it may concern:

Be it known that I, ULRICH EBERHARDT, a citizen of the United States, residing at Newark, county of Essex, State of New Jersey, have invented a certain new and useful Design for a Ram for Crank Planing-Machines, fully described and represented in the following specification and the accompanying drawings, forming a part of the same.

This invention consists in a novel shape or configuration for the reciprocating ram used for carrying the tool in crank planing-machines.

The nature of this design will be understood by reference to the annexed drawings, in which--

Figure 1 is a plan of a ram embodying my design; Fig. 2, a cross-section of the same on line 2 2 in Fig. 1, and Fig. 3 is a side elevation of the ram.

The ram is represented with a longitudinal body A, having laterally-projecting flanges B at the bottom, circular head C at the front

end, longitudinal slot D, extended vertically through the body, and horizontal longitudinal ribs E along the edges of the slot D at the top of the body.

The shape which I claim for my design includes the longitudinal body A, provided with vertical slot D, and having the circular head C at the front end, laterally-projecting flanges B at the bottom, and laterally-projecting ribs E at the top, substantially as shown in the drawings.

Having thus set forth the invention, what is claimed herein is--

The design for ram of crank planing-machine, substantially as shown and described.

In testimony whereof I have hereunto set my hand in the presence of two subscribing witnesses.

ULRICH EBERHARDT.

Witnesses:

ELMER E. MERRITT,
EDWARD F. KINSEY.
